UNITED STATES PATENT OFFICE.

FRANK I. JOYCE, OF DAYTON, OHIO.

HYDRAULIC JACK.

SPECIFICATION forming part of Letters Patent No. 398,784, dated February 26, 1889.

Application filed April 12, 1888. Serial No. 270,469. (No model.)

To all whom it may concern:

Be it known that I, FRANK I. JOYCE, of Dayton, in the county of Montgomery and State of Ohio, have invented certain new and 5 useful Improvements in Hydraulic Jacks, of which the following is a specification.

One object of my invention is to provide a jack so constructed that the valves and working parts can be easily reached and adjusted. 10 Another object of my invention is to provide a hydraulic jack which can be operated in a horizontal, vertical, or in an inclined position, as desired, all of which will be set forth in the description of the accompanying drawings, making a part of this specification, of 15 which—

Figure 1 is a central vertical section. Fig. 2 a horizontal section on line x x , Fig. 1. Fig. 3 is a similar section to Fig. 1, and showing 20 the plunger in elevation and at rest in its upward limit of movement.

A represents the frame of the jack.

B represents the base of the frame.

C represents a hollow cylinder, which is 25 secured to the frame A by the nut D.

E represents a packing inserted between the end of the cylinder C and the base B for securing a tight joint.

H represents a tube fitting within the cylinder C. This tube H is secured to the head 30 of the jack. At the other end of this ram, and secured to it by the nut S, is the head J, on top of which, at T, rests the load to be lifted.

35 1 represents the plunger-rod, provided at its lower end with the packing 2 and 2', secured by the nut 3 and forming the plunger, as shown in Figs. 1 and 2. The plunger-rod

1 is provided at its other end with a crank-pin, 8, which is securely attached thereto.

40 4 represents a many-sided rock-shaft provided with journals 5, which work in bearings in the head J.

6 represents a crank-arm securely attached 45 at one end to the many-sided rock-shaft 4, and at its other end provided with forks 7, in which journals the crank-pin 8, which, as before said, is securely attached to the plunger-rod 1.

9 represents a crank-head securely attached

to the rock-shaft 4, and provided with an opening into which a lever may be inserted to operate the plunger-rod 1.

It is desired in hydraulic jacks to have them work horizontally as well as vertically. To accomplish this, I have arranged the parts in 55 the manner shown in Figs. 1 and 2.

10 represents a cylindrical nut tapping into the head of the ram 11. It is hollowed out so as to form a receptacle for the spiral spring 12, and is pierced with the orifices 27 and the 60 guide-bearing 33.

14 represents a valve which seats against the top of the valve-chamber 15.

13 represents the stem of valve 14. It projects downward into the guide-bearings 33 65 and upward through the guide-bearing 34 into the plunger-chamber 17.

16 represents ports or passages leading from the valve-chamber 15 up into the plunger-chamber 17, and so placed that when the valve 70 14 is against its seat it closes the ports 16 between the two chambers 15 and 17.

18 represents a passage leading from the plunger-chamber 17 to the second valve-chamber, 19. This valve-chamber also is secured 75 in the head of the ram by means of a cylindrical nut, 20, which is closed at the bottom and hollowed out to form a receptacle for the spiral spring 21.

22 represents a valve which seats against 80 the top of the valve-chamber 19. It is normally held closed by the spring 21.

23 represents the stem of valve 22. It passes up through a guide-bearing in the head of the ram into the reservoir 25, so that the valve 85 may be forced from its seat, as will be explained hereinafter.

24 represents a passage leading from the valve-chamber 19 to the fluid-reservoir 25 inside the ram H, and so placed that when the 90 valve 22 is seated it closes the passage 24 between the valve-chamber 19 and the fluid-reservoir 25.

26 represents a fluid-chamber below the ram and within the cylinder C, into which the fluid 95 is pumped from the chamber 25 to lift the ram.

It will be observed that the valves may be

readily reached for adjustment by removing the ram from its cylinder and unscrewing the nuts 10 and 20, when the valves can be taken out and examined and replaced. This I believe to be a great advantage over other constructions of hydraulic jacks hitherto employed.

In order to prevent leakage of the fluid, I have provided the following devices for packing the journals of rock-shaft 4, and they are constructed so as to allow the rock-shaft to be easily taken out or put in. The frame of the head J is provided with the two bosses K and L. Boss K is recessed, so as to form a seat for the packing-ring M, against which the shoulder O of the rock-shaft bears. The opposite boss, L, is provided with a similar recess and a packing-ring, N.

P Q represent cylindrical jam-nuts, their outer periphery forming the journal of the rock-shaft, their inner periphery being provided with threads which engage with threads on rock-shaft 4, thus drawing the shoulder O and the nut Q firmly against the packing M and N to form a liquid-tight joint. As the cylinder of the rock-shaft journaling in boss K is of the same or larger diameter than the diagonal diameter of the many-sided rock-shaft, it can be readily removed from or inserted into the opening in crank-arm 6.

The operation of this jack is as follows: The fluid to be employed for raising the ram is in chamber 25. The plunger 1 is operated by oscillating shaft 4. When plunger 1 is lifted, it tends to cause a vacuum in the plunger-chamber 17, which communicates with the passage 18 to the valve-chamber 19. This causes the valve 22 to recede from its seat and the fluid flows from chamber 25 through passage 24, valve-chamber 19, and passage 18 into plunger-chamber 17, filling the space under the plunger. When the plunger arrives at this upward point of its stroke, it is in position shown in Fig. 3, and both valves will be normally closed by the springs 12 and 21. As soon as the plunger descends the pressure is increased in the plunger-chamber 17 and adjoining passages and causes the valve 22 to press more firmly on its seat, preventing the escape of the fluid back into chamber 25. At the same time it causes the valve 14 to recede from its seat, and the fluid is forced from the plunger-chamber 17 through the orifices 16 into the valve-chamber 15, thence through the orifices 27 into the chamber 26, raising the ram.

The plunger-rod 1 is provided with a lug, 28, which is rigidly attached thereto in such a position that when the plunger presses down onto the valve-stem 13 of the valve 14 the lug 28 will press on the stem 23 of valve 22. With this in mind, the operation of lowering the load will be readily understood. The plunger is lowered so that it presses on valve-stem 13 and causes the valve 14 to be removed from its seat. At the same instant the lug 28 presses

down on valve-stem 23 and causes the valve 22 to be removed from its seat also. The passages between chambers 26 and 25 are now all connected, and the fluid flows from chamber 26, under pressure of the load or weight of the ram, through orifices 27, into valve-chamber 15, thence through orifices 16 into plunger-chamber 17, thence through passage 18, valve-chamber 19, and side passage, 24, into chamber or reservoir 25, and as the fluid flows out of chamber 26 the ram will descend.

The plunger-rod 1 is made smaller than the plunger, so that it may rock a sufficient amount to accommodate itself to the oscillation of the crank-arm 6 in its operation.

The ram-head 11 is provided with a packing, 30, at the bottom, which is held in position by the nut 31 engaging with threads on the head 11.

The passage 24 opens into the reservoir 25 at its extreme side, so that when the jack is placed in a horizontal position, with this passage down, its opening will be submerged until nearly all the fluid in the chamber 25 has been pumped out; and in order that the fluid may be compelled to flow through the passage 24, even after the surface of the fluid has sunk below the central horizontal line of the plunger-chamber, I have provided an inverted packing, 2', on the plunger, so that when the plunger 1 is raised to fill the chamber 17 this inverted packing 2' will spread and cause a perfect vacuum in the chamber 17.

Having described my invention, what I claim is—

1. In a hydraulic jack, the ram-head 11, having both inlet-valve 22 and outlet-valve 14 placed therein, as and for the purposes specified.

2. In a hydraulic jack, the combination, with the chambers 25 and 26, of the ram-head 11, having an inlet-valve chamber, 19, and a passage, 24, leading from the extreme side of the chamber 25 to the inlet-valve chamber 19, to permit the working of the jack in a horizontal or inclined as well as in a perpendicular position, substantially as described.

3. In the pump of a hydraulic jack, the combination, with the ram-head 11, having inlet and outlet valves located therein, and a side passage, 24, provided with valve 22, of a plunger, 1, having the inverted cup-packing 2', for the purpose of securing a perfect vacuum in the plunger-chamber, substantially as described.

4. In a hydraulic jack, the combination, with the chambers 25 and 26, of the ram-head 11, having valve-chambers 15 and 19, plunger-chamber 17, and passages 24 and 18, leading from the chamber 25 through said valve-chambers to the plunger-chamber, the valves 14 and 22, having stems 13 and 23, the valve-springs 12 and 21, and the plunger 1, having an inverted cup-packing, 2', and provided with a lug, 28, substantially as described.

5. In a hydraulic jack, the combination of

the tubes C H, the chambers 25 and 26, the ram-head 11, having valve-chambers 15 and 19, plunger-chamber 17, and passages 24 and 18, leading from the side of the upper chamber, 25, through the valve-chambers 19 and 15, into the plunger-chamber, the valves 14 and 22, having stems 13 and 23, the nuts 10 and 20, and springs 12 and 21, for supporting said valves, the plunger 1, provided with lug 28 and packing 2 and 2', and the packing 30 and nut 31 at the lower end of the ram-head, substantially as described.

6. In a hydraulic jack, the combination, with the head J and plunger 1, of the bosses K L, the rock-shaft 4, having journals 5, supported in said bosses and provided with cranks 6 and 9, the packing-rings M N, and the jam-nuts P Q, substantially as described. 15

In testimony whereof I have hereunto set my hand.

FRANK I. JOYCE.
